OPAQUE LIQUID DETERGENT COMPOSITIONS
Frank E. Carroll, Glen Rock, N.J., and Ralph R. Sepulveda, Bronx, N.Y., assignors to Lever Brothers Company, New York, N.Y., a corporation of Maine
No Drawing. Filed Aug. 18, 1961, Ser. No. 132,289
2 Claims. (Cl. 252—110)

The present invention relates to liquid detergent compositions and more particularly to opaque liquid detergent compositions especially adapted for the cleansing of hard surfaces.

While translucent or transparent liquid synthetic detergent compositions are known, the provision of opaque liquid detergent compositions is desirable in that such compositions present a more attractive and more viscous appearance which the consumer associates with greater cleansing power. The formulation of opaque liquid detergent compositions, however, is not a simple matter. Thus if one attempts to prepare opaque liquid detergent compositions by adding opacifying agents to clear hard surface liquid cleansers, the resulting products are unsatisfactory due to their instability. This is brought on by the coagulation and separation of the opacifying agents from the liquid.

It is, therefore, an object of the present invention to provide opaque liquid detergent compositions especially adapted for the cleansing of hard surfaces. Another object is to prepare opaque liquid detergent compositions which are free of coagulation and phase separation and hence are stable. These and other objects of the present invention will be apparent as the description proceeds.

It has now been found that stable, opaque liquid detergent compositions are formed when certain soaps, a nonionic detergent and a complex phosphate are combined in critical proportions in an aqueous medium. The explanation for this phenomenon is not clearly known, but it is believed that a physical complex resulting in an opaque liquid occurs when these ingredients are combined. The foregoing ingredients supply the cleaning, wetting, and foaming properties of the liquid. In addition, other ingredients, such as anionic detergents, sequestering agents, dyes and perfume, may be added, if desired.

Suitable soaps are the salts of fatty acids having from 16 to 18 carbon atoms, for example, the sodium, potassium and ammonium salts of tallow fatty acids (40 iodine value), palmitic acid, oleic acid and stearic acid.

The nonionic detergent may include the mono- and di-lower alkylolamides of fatty acids having from 12 to 18 carbons, the condensation product of lauryl alcohol with about 5 moles of ethylene oxide, and nonylphenol condensed with from 1 to 5 moles of ethylene oxide. Examples of suitable alkylolamides include lauric diethanolamide (LDA), lauric isopropanolamide (LIPA), oleic diethanolamide (ODA), myristic diethanolamide (MDA), tallow diethanolamide (TDA) and lauric monoethanolamide (LMEA).

The complex phosphate component may be tetrapotassium pyrophosphate or pentapotassium tripolyphosphate.

The amounts of the components present in the compositions will vary with the specific phosphate, the nonionic detergent, the type of soap and its cation, and the

2

total concentration of soap and nonionic detergent. No general relationship can be established for combining soap, complex phosphate and nonionic detergent to give an opaque liquid.

5 The degree of opacity also varies with the type of soap, the type of nonionic detergent and the concentration of phosphate, the liquids formed ranging from transparent cloudy liquids to transparent opaque liquids to very opaque liquids. A liquid is described as a transparent cloudy liquid if the outline of an object held behind a 4 ounce sample bottle of the liquid can be seen on looking through the liquid even after the liquid has been gently agitated. If an object held behind a 4 ounce sample bottle of the liquid can be seen on looking through the liquid which has stood overnight but it cannot be seen after gentle agitation of the liquid, due to its increase in opacity, the liquid is characterized as a transparent opaque liquid. If an object held behind a 4 ounce sample bottle of the liquid cannot be seen on looking through the liquid after allowing the liquid to stand overnight, the liquid is described as an opaque liquid.

Taking the above variables into consideration, the compositions of the present invention comprise a total of from about 3.5% to about 14% by weight of soap plus 25 nonionic detergent, and from about 5% to about 20% by weight of complex phosphate. In general, as the ratio of nonionic detergent to soap decreases, the amount of phosphate which can be used increases.

The following examples illustrate the criticality of the 30 number and nature of the components necessary for preparing the opaque liquid detergent compositions of the present invention.

In these examples LDA stands for lauric diethanolamide and TKPP stands for tetrapotassium pyrophosphate.

TABLE I.—LIQUID COMPOSITIONS CONSISTING OF LDA, TALLOW SOAP, TKPP AND WATER

Ingredients	Percent by weight							
	A 1	B 2	C 3	D 4	E 5	F 6	G 7	H 8
LDA	4			4	4		4	4
Na lauroate		3		3		3		3
Na laurate							3	
TKPP			10		10	10	10	10
Water	96	97	90	93	86	87	83	83
Viscosity (cps.)	100	100	100	100	100	100	100	100
	145		4	95		190		155

50 Description of composition:

¹ Transparent slightly turbid liquid. ² Solid paste. ³ Clear homogeneous liquid. ⁴ Clear homogeneous liquid. ⁵ LDA separates as solids at top of liquid. ⁶ Slightly cloudy transparent gel. ⁷ Clear homogeneous liquid. ⁸ Opaque liquid.

55 The data in the foregoing table show that an opaque liquid is formed when lauric diethanolamide, sodium tallow soap and tetrapotassium phosphate are combined in an aqueous medium. The behavior of the individual components in water (Examples A, B, and C) or of combinations of two of the ingredients (Examples D, E, and F) would not indicate that an opaque liquid could be formed by combining the three components. Examples

60 G establishes that even when the three components are present, the particular soap employed is critical to the formation of an opaque liquid. Example H is an opaque

3

liquid detergent composition according to the present invention.

The following table lists compositions based on lauric isopropanolamide (LIPA), sodium tallow soap, tetrapotassium pyrophosphate (TKPP) and water.

TABLE II.—LIQUID COMPOSITIONS CONSISTING
OF LIPA, TALLOW SOAP, TKPP AND WATER

Ingredients	Percent by weight				
	I 1	J 2	K 3	L 4	M 5
LIPA	4	4	4	4	4
Na tallowate		3			3
Na laurate				3	
TKPP			10	10	10
Water	96	93	86	83	83
Viscosity (cps.)	100	100	100	100	100

Description of composition:

¹ LIPA separates from liquid. ² Transparent gel. ³ LIPA separates from liquid. ⁴ Separates into two nearly equal layers. ⁵ Opaque liquid.

The data in this table are similar to that of Table I in that the behavior of the individual components in water or combination of two of them would not indicate that an opaque liquid could be formed by combining the three components. Example M of the invention compared with Example L demonstrates that the soap, nonionic detergent and complex phosphate must be selected in accordance with the present invention in order to form an opaque liquid.

The liquid compositions described herein were made by dissolving the soap in water or by neutralizing the fatty acid with an alkali metal or ammonium hydroxide to form soap. The nonionic detergent was then added to the soap solution followed by the complex phosphate which had been predissolved in water. The liquid compositions can also be made by adding the complex phosphate, predissolved in water, to the soap solution followed by the nonionic detergent. Heat was used when necessary to dissolve the soap, to melt the nonionic detergent and to facilitate the mixing of the ingredients.

An example of a formulation containing an anionic detergent, sequestering agent and perfume is as follows:

Example N

Ingredients:	percent by weight	50
Sodium dodecylbenzene sulfonate	1.25	
Ammonium tallow soap (40 IV)	2.95	
Lauric diethanolamide	2.85	
Lauric isopropanolamide	1.00	
Tetrapotassium pyrophosphate	10.00	55
Versene (ethylene diamine tetraacetic acid- sequestering agent)	0.10	
Perfume	0.15	
Miscellaneous	0.40	
Water	81.30	60
	100.00	

pH (as is)—10.6

Viscosity (c.p.s.)—120.0

Specific gravity—1.090

The dodecylbenzene sulfonic acids and tallow fatty acids used in this example were neutralized with 0.63% of ammonium hydroxide, assaying 28% NH₃, and 1.13% of 50% sodium hydroxide solution. The ammonium and sodium cations are believed to be combined as shown in the above formulation. In addition, the ammonia gives the product an ammoniacal odor.

The following example illustrates the use of pentapotassium tripolyphosphate.

4

Ingredients:	percent by weight
Ammonium tallow soap (40 IV)	2.95
Lauric diethanolamide	2.85
Lauric isopropanolamide	1.00
Pentapotassium tripolyphosphate (anhydrous)	10.00
Distilled water, to 100%.	

The pH of the foregoing composition was adjusted to 10.5 by addition of ammonium hydroxide.

10 Small amounts of sodium pyrophosphate or sodium tripolyphosphate may be added to the compositions of the present invention. While it is difficult, in view of the aforementioned variables to specify an exact limit for these
15 additives, the amount can be at least that which is equivalent in sodium content to the amount of sodium soap in the formula, if the sodium soap is replaced by a potassium soap.

The following examples further illustrates the present invention without, however, limiting the same thereto. In these examples the total concentration of nonionic detergent plus soap is indicated and for various ratios of nonionic detergent to soap within this concentration, the concentrations of complex phosphate which produce opaque liquid detergent compositions are indicated. By plotting the ratio of nonionic detergent to soap against complex phosphate concentration and connecting the points, a polygonal figure is obtained. Any point within the perimeter of the polygonal figure so obtained will produce an opaque liquid detergent and it is the area within such perimeter which is the subject matter of the present invention. In the following examples, the abbreviations used for the alkylolamides are those identified herein above while NPE-1 and NPE-5 represent nonyl-phenol condensed with 1 and 5 moles of ethylene oxide, respectively.
